UNITED STATES PATENT OFFICE.

JOSEPH G. C. MANTLE, OF LEONIA, NEW JERSEY.

ROTARY CHARGE CHAMBER.

Original application filed June 30, 1923, Serial No. 648,783. Divided and this application filed June 8, 1926. Serial No. 114,383.

This invention relates to internal combustion engines of either the explosion or the continuous combustion type and, also, such as may be operated as of either type.

5 It is a division of my application for a patent on internal combustion engines, Serial No. 648,783, filed June 30, 1923.

This invention is a rotary set of chambers into each of which, during successive compressive strokes of the engine, a charge of compressed working fluid consisting of air and fuel or air alone, as the case may be, is admitted from the compression chamber and from each of which, during successive strokes of the engine, a charge is released to the working chamber. The charge of compressed working fluid when released from its chamber may be in the same condition as when admitted or it may be in any stage of its combustion. In other words, a charge is admitted to one of the chambers during each compression cycle, and a charge is released from its chamber during each working cycle, the charge being either in the same condition as upon its admittance or in any stage of combustion. For convenience each of the chambers will be termed a charge-chamber. Each charge-chamber has an inlet and an outlet for communication with the outlet and inlet of the compression chamber and the working chamber, respectively. To dispense with valves for opening and closing the inlets and outlets of the charge-chambers, and the mechanism necessary for their operation, and also to avoid the attendant noise of the same, the set of charge-chambers is continuously rotated by the engine, and while rotating the inlets and outlets communicate with the outlet and inlet of the compression chamber and working chamber, respectively. This rotation is effected by any suitable means in connection with the engine crank-shaft, and rotates twice or more times to each rotation of the crank-shaft in accordance to the number of charge-chambers contained in the set. The set of charge-chambers is applicable to all engines which have separate compression and working chambers, and also to such engines wherein the compression and expansion of the working fluid is effected on opposite faces of a piston in one chamber serving both as a compression chamber and a working chamber.

One of the several uses or objects of this invention is its embodiment in a very high speed and noiseless engine which may be operated on the continuous combustion plan and having a working cycle extending through both strokes of the pistons operating but a single crank.

This invention will now be described in reference to the drawings:

Figure 1 is a longitudinal sectional elevation of a tandem engine embodying a set 65 of charge-chambers.

Figure 2 is a transverse section through the inlets of a set of charge-chambers, on the line 2—2 of Figure 1.

Figure 3 is a transverse section through 70 the outlets of the same set of charge-chambers, on the line 3—3 of Figure 1.

Figure 4 is a transverse section on the line 4—4 of Figure 1, through the portion of a rotary valve which opens and closes 75 the inlet of the compression chamber.

Figure 5 is a transverse section on the line 5—5 of Figure 1 through the portion of a rotary valve which opens and closes 80 the exhaust outlet.

Figure 6 is a transverse section on the line 6—6 of Figure 1, through the inlet and outlet of the auxiliary working chamber.

Figure 7 is a transverse section on the line 7—7 of Figure 1, through the outlet 85 of the working chamber and through the portion of a rotary valve which opens and closes that outlet.

Figure 8 is a transverse section through the inlets of a set of three charge-chambers. 90

Figure 9 is a transverse section through the outlets of the same set of three charge-chambers.

Figure 10 is a transverse section through the inlets of another set of two charge-chambers. 95

Figure 11 is a transverse section through the outlets of the preceding set of two charge-chambers.

Referring to Figure 1: *z* and *y* are two 100 cylinders in tandem having pistons *P* and *Q* rigidly connected by the piston rod *S*. piston *Q* carries a wrist pin *f* by which a connecting rod *c* connects the piston *Q* to the crank pin *a* of the crank-shaft *b* 105 of the engine. Connected with cylinder *y* are two cylindrical chambers *d* and *e*. Cylinder *y* and chambers *d* and *e* have a com-

mon cover *g* which is provided with an inlet *I* opening to chamber *e*. The chamber *e* has an outlet *X* serving as the exhaust outlet of the engine. Chamber *e* is provided 5 with a rotary valve *h* having portions, adapted to open and close communication between the cylinders *z* and *y* through the chamber *e*, to open and close communication between the cylinder *y* and the inlet *I*, and 10 to open and close communication between the cylinder *y* and the exhaust outlet *X*. Chamber *d* contains a set of charge-chambers, each charge-chamber *R* and *L* has an inlet adapted for communication with the 15 outlet *j* of the cylinder *y* and with an outlet for communication with the inlet *k* of the cylinder *z*, during the rotation of the set of charge chambers (see Figures 2 and 3). A preferred form comprises a hollow 20 cylindrical body *i* provided at its inner cylindrical portion with chambers *R* and *L* extending upwardly and downwardly in a spirally disposed manner and terminating in the aforementioned inlets and outlets, respectively. Connected to the lower end of 25 body *i* is a rod *l* on the lower end of which is secured a worm-wheel *m* meshing with a worm *n* secured to a shaft *o*. Similarly, to the lower end of the rotary valve *h* is a rod 30 *p* on the lower end of which is secured a worm-wheel *q* meshing with a worm *r* secured to a shaft *s*. Secured to the shafts *o* and *s* and the crank-shaft *b* are chain-wheels *t* connected together by a chain *t'*. 35 The gears *m* and also *n* and the gears *q* and *r* are so relatively proportioned, *m* to *n* and *q* to *r*, that to each two rotations of the crank-shaft *b* there are two rotations of the valve *h* but only one rotation of the body *i*. In 40 other words, one rotation of the crank-shaft imparts one rotation to the valve, but imparts only one-half of a rotation to the set of charge-chambers. Consequently, during each compression stroke (upward stroke) 45 one or the other of the charge-chambers is charged with compressed working fluid from the cylinder *y* above the piston *P* through its outlet *j*, and during each working stroke (downward stroke) a charge of compressed 50 working fluid is released from one or the other of the charge-chambers to the cylinder *z* through its inlet *k*. The space in cylinder *y* above the piston *P* serves as the compression chamber the space in cylinder *z* above 55 the piston *Q* serves as the working chamber, and the space in cylinder *y* below the piston *P* serves as an auxiliary working chamber. There is a one stage compression cycle, and 60 a two stage working cycle; during the first stage of the working cycle the working fluid expands between the upper end of cylinder *z* and the top of piston *Q*; during the second stage it expands between the top of piston *Q* and the bottom of piston *P*, the valve *h* 65 then being in position permitting its pas-

sage from cylinder *z* to cylinder *y* and the outlet of a charge-chamber is open to cylinder *z* during both of the stages.

The action of the valve *h* is as follows: the portion *n* closes the outlet of cylinder *z* 70 shortly before the commencement of the downward stroke and opens it shortly before the end of the stroke, and closes it shortly before the end of the upward stroke, and thus confines a portion of the working fluid to cushion the piston *Q*. The portion *m* closes the exhaust outlet *X* shortly before the end of the downward stroke and thus confines a portion of the working fluid to cushion the piston *P* and 75 it opens the exhaust outlet *X* shortly before the end of the upward stroke. The portion *t* closes the inlet of cylinder *y* shortly after the commencement of the upward stroke and opens it at an early part of the downward 80 stroke.

The action of the set of charge-chambers is as follows: Referring to the position of parts as shown in Figure 1, a charge of compressed working fluid was admitted from 90 the compression chamber into charge-chamber *R* during the preceding upward stroke and its inlet closed to the compression chamber immediately before the end of that stroke. By inspection of Figures 2 and 3, 95 it will be seen that its outlet is closed, but is about to open to the working chamber. Remembering that the set of charge-chambers rotates through only 90° while the crank-shaft rotates through 180°, it will be 100 seen that during the early part of the next upward stroke the charge-chamber *L* will be open to the compression chamber and at the end of that stroke the charge-chamber *L* will occupy the position shown of charge-chamber *R*. It will also be seen that each 105 charge is confined in its charge-chamber for the duration of but a very small part of a rotation of the crank-shaft. In other words, the charge is released almost immediately 110 after its closure in its charge-chamber.

But a set of charge-chambers may consist of three or more charge-chambers, as shown in Figures 8 and 9, which shows corresponding sections to Figures 2 and 3 of a set of 115 three charge-chambers substituting them. In this case the gears *m* and *n* are so proportioned that the body *i* rotates through 120° while the crank-shafts make one rotation. Referring to Figures 1, 8 and 9, a 120 charge was admitted to charge-chamber *R* during the preceding upward stroke and is confined in its charge-chamber. It will be seen that its outlet (see Figure 9) will not open to the working chamber until it has 125 rotated through 120°. In other words, it is confined in its charge-chamber for the duration of a rotation of the crank-shaft. As the inlets and outlets of the three charge-chambers are equally spaced around the cen- 130

ter of rotation it is also true in respect to the other charge-chambers. Also, it is obvious with a set of charge-chambers comprising a still greater number and having a correspondingly less angular movement relative to that of the crank-shaft that each charge is confined during a relatively greater angular movement of the crank-shaft.

The set of charge-chambers has now been described in its application to engines wherein in the termination of the compression stroke is synchronous with the commencement of the working stroke, and it will now be described in its application to engines wherein in the commencement of the compression stroke is synchronous with the commencement of the working stroke. Figure 10 is a section through the inlets of a set of charge-chambers as in Figure 2 except that the piston effecting the compression stroke is at the commencement instead of the termination of its stroke. Figure 11 is a section through the outlets as in Figure 3 with the piston effecting the working stroke at the commencement of its stroke. The set of charge-chambers has an angular movement of one-half that of the crank-shaft as already described in reference to Figures 2 and 3. The inlet of charge-chamber R is about to open to the compression chamber of the piston of which is at the commencement of its compression stroke and the outlet is already closed to the working chamber the piston of which is also at the commencement of a working stroke. During this compression stroke the inlet of the charge-chamber R will receive and confine a charge of compressed working fluid. The following edge w of the inlet and the leading edge x of the outlet will rotate through 90° and by that amount be in a position beyond that shown in Figures 10 and 11. At the end of the next 90° of movement the following edge w and the leading edge x of the charge-chamber R will occupy the positions shown in Figures 10 and 11 of charge-chamber L. Therefore, the charge was confined in charge-chamber R during 90° of its angular movement which amounts to one-half of a rotation of the crank-shaft. As the inlet and outlets are equally spaced around their center of rotation this is also true of charge-chamber L.

Now the speed of an internal combustion engine is dependent upon the speed of combustion of the compressed working fluid. In an explosion engine the combustion is started by igniting the compressed working fluid, and in a continuous combustion engine by adding the fuel to the compressed working fluid, and in either type by the use of well known means, viz; by an ignition plug or a fuel nozzle attached to, and operating through a hole in the working chamber of the engine. This may be done through the

hole V shown in Figure 1. By inspection of Figures 3, 9 and 11, it will be seen that there is provided in connection with the set of charge-chambers a hole v adapted for the attachment of either the well known ignition plug or the well known fuel nozzle, and through which hole the combustion of the compressed working fluid may be commenced and even completed during its rotation and confinement in its charge-chamber prior to its release to the working chamber. With either a slowly igniting mixture or, in a continuous combustion engine, this is a great advantage for the speed of the engine is not then limited by the speed of combustion. It has been shown that the duration of its confinement may be increased without decreasing the angular velocity of the crank-shaft and that a charge of compressed working fluid may be confined in its charge-chamber during any number of strokes of the piston in accordance to the number of charge-chambers comprised in the set of the same.

The set of chambers may also be used in an engine which may be operated either as an explosion or as a continuous combustion one. The essential difference in the operation of the two types is the degree of compression of the working fluid and this is determined by the relative cubical capacity of charge-chamber and compression chamber. The chamber d is adapted for the interchange of sets of charge-chambers having different cubic capacity. Also, the charge-chambers, by mere mechanical skill, may be so constructed that their cubical capacity may be readily changed. Also, in the holes u or V either the well known ignition plugs or fuel nozzles along with their accessories may be used as desired.

Having thus fully described the invention, what I claim as new and desire to secure by Letters Patent is:

1. In an internal combustion engine of the type wherein a reciprocating piston imparts a rotary motion to the power shaft of the engine, a compression chamber and a working chamber having a common axis, a piston in each of the said chambers and making strokes, in unison, alternately in direction to and from the said power shaft, a plurality of charge chambers each adapted to contain and confine a charge of working fluid, means by which, during each stroke in the same direction of the said pistons, a charge of working fluid is compressed from the said compression chamber and confined in one of the said plurality of charge chambers, and also into each of them, successively, during successive strokes in the same direction of the said pistons, and means by which, during each stroke in the same direction of the said piston, a charge of working fluid is released from one of the said plurality of

charge chambers into the said working chamber, and also from each of them, successively, during successive strokes in the same direction of the said piston, the said plurality of charge chambers rotating as a body and on an axis substantially parallel to the common axis of the said compression and working chambers.

2. In an internal combustion engine of 10 the type wherein a reciprocating piston imparts a rotary motion to the power shaft of the engine, a compression chamber and a working chamber having a common axis, a piston in each of the said chambers and 15 making strokes, in unison, alternately in direction to and from the said power shaft, a plurality of charge chambers each adapted to contain and confine a charge of working fluid, means by which, during each rotation 20 of the said power shaft, a charge of working fluid is compressed from the said compression chamber and confined in one of the said plurality of charge chambers, and also into each of them, successively, during successive 25 rotations of the said power shaft, and means by which, during each rotation of the said shaft, a charge of working fluid is released from one of the said charge chambers into the said working chamber, and also from 30 each of them, successively, during successive rotations of the said power shaft, the said plurality of charge chambers rotating as a body and on an axis substantially parallel to the common axis of the said compression 35 and working chambers.

3. In an internal combustion engine of 40 the type wherein a reciprocating piston imparts a rotary motion to the power shaft of the engine, a compression chamber and a working chamber having a common axis, a piston in each of said chambers and making 45 strokes, in unison, alternately in direction to and from the said power shaft, a plurality of charge chambers each adapted to contain and confine a charge of working fluid, means by which, during each rotation of the said power shaft, a charge of working fluid is compressed from the said compression chamber and confined in one of the said plurality of charge chambers, and also into each of them, successively, during successive 50 rotations of the said power shaft, and means by which, during each rotation of the said power shaft a charge of working fluid, is released from one of the said plurality of charge chambers into the said working chamber, and also from each of them, successively, during successive rotation of the said power shaft, the said plurality of 55 charge chambers rotating as a body and making not more than one rotation to each 60 two rotations of the said power shaft.

4. In an internal combustion engine of the type wherein a reciprocating piston imparts 65 a rotary motion to the power shaft of the

engine, a compression chamber and a working chamber having a common axis, a piston in each of said chambers and making strokes, in unison, alternately in direction to and from the said power shaft, a plurality of 70 charge chambers rotating as a body on an axis substantially parallel to the said common axis of the compression and working chamber and each of said charge chambers adapted to contain and confine a charge of 75 working fluid; means by which, during each stroke in the same direction of the said piston, a charge of working fluid is compressed from the said compression chamber and confined in one of the said plurality of charge 80 chambers, and also into each of them successively, during successive strokes in the same direction of the said piston, means by which, during each stroke in the same direction of the said pistons, a charge of working fluid is released from one of the said plurality of charge chambers into the said working chamber, and also from each of them, successively, during successive strokes in the same direction of the said piston, and means by which each charge of working fluid is confined in its charge chamber for a duration greater than that of one stroke of the 85 said pistons.

5. In an internal combustion engine of 90 the type wherein a reciprocating piston imparts a rotary motion to the power shaft of the engine, a compression chamber and a working chamber having a common axis, a piston in each of said chambers and making 95 strokes, in unison, alternately in direction to and from the said power shaft, a plurality of charge chambers rotating as a body and on an axis substantially parallel to the said common axis of the compression and working 100 chambers and each of said plurality of charge chambers adapted to contain and confine a charge of working fluid, means by which, during each rotation of the said power shaft, a charge of working fluid is 105 compressed from the said compression chamber and confined in one of the said plurality of charge chambers, and also into each of them, successively, during successive rotations of the said power shaft, means by which, during each rotation of the said power shaft, a charge of working fluid is 110 compressed from the said compression chamber and confined in one of the said plurality of charge chambers, and also into each of them, successively, during successive rotations of the said power shaft, means by which, during each rotation of the said power shaft, a charge of working fluid is 115 released from one of the said plurality of charge chambers into the said working chamber, and also from each of them, successively, during successive rotations of the said power shaft, and means by which a combustion of the charge of working fluid is effected prior to its release to the working 120 chamber and during its confinement in its 125 charge chamber.

6. In an internal combustion engine of the type wherein a reciprocating piston imparts a rotary motion to the power shaft of the engine, a compression chamber and a work- 130

ing chamber having a common axis, a piston in each of said chambers and making strokes, in unison, alternately in direction to and from the said power shaft, a plurality of 5 charge chambers rotating as a body and on an axis substantially parallel to the said common axis of the compression and working chambers and each of said plurality of charge chambers adapted to contain and contain 10 fine a charge of working fluid, means by which, during each rotation of the said power shaft, a charge of working fluid is compressed from the said compression chamber and confined in one of the said plurality of 15 charge chambers, and also into each of them, successively, during successive rotations of the said power shaft, means by which, during each rotation of the said power shaft, a charge of working fluid is released from one of the said plurality of charge chambers 20 into the said working chamber, and also from each of them, successively, during successive rotations of the said power shaft, and means by which the said release of the charge to the working chamber is maintained 25 during two successive strokes of the said pistons.

In testimony whereof I have hereto signed my name this 7th day of June, 1926.

JOSEPH G. C. MANTLE.
